UNITED STATES PATENT OFFICE.

EDMUND O. SCHWEITZER, OF CHICAGO, ILLINOIS.

LIGHTING FIXTURE.

Application filed April 4, 1923. Serial No. 629,745.

My invention relates to lighting fixtures and more particularly to electric lighting fixtures of the wall or side bracket type.

In fixtures of this sort there is usually a side or wall bracket for attachment to the wall or other vertical support and the conductors usually lead directly to the lamp socket or connection at the fixture. It is often desirable to connect an appliance circuit or other electrical device to the single service outlet leading to such a fixture. Where the outlet leads directly to the fixture the only possible place of connection of another device thereto is at the fixture itself. Multiple connecting members such as those comprising a plug having a plurality of sockets or other outlets or take-off connections are unsuited for this purpose, particularly where the artistic or esthetic effect is predominant.

A shade is usually desirable and in such fixtures the shade is frequently not large enough to accommodate the type of multiple connecting member which is inserted into the outlet at the fixture and projects into the shade. Even if the shade is large enough, attachment of the connecting member is difficult and when attached the artistic effect of the fixture is impaired. The lamp or light is not positioned properly in the shade, but is usually positioned off to one side and the appliance circuit conductors extend up into the inside of the shade. The connecting members which provide an additional take-off connection outside the shade are unsightly and require arrangement of the shade out of its desired position.

The aim of my present invention is to provide a simple inexpensive fixture of this sort with an additional built-in outlet or take-off connection.

In the preferred form of the invention I provide a bracket for mounting upon a wall or other vertical support. A socket supported above the mounting bracket by a hollow stem or rod forms a mounting for the fixture shade. This socket has a downwardly opening portion for supporting a lamp vertically in the shade and an aligned upwardly opening portion for the attachment of an appliance or other electrical circuit. The conductors which lead to the socket and take-off connection at the fixture extend from the wall through and

are masked by the mounting bracket and extend up through the hollow socket supporting stem to the lamp and take-off terminals at the socket. The additional take-off provision which is a built-in part of the fixture permits convenient connection of an appliance or other additional circuit to the fixture without impairing the artistic or esthetic effect of the fixture and irrespective of the size of shade employed and without requiring changing the positioning of the shade. The lamp is at all times positioned vertically in the center of the shade and arrangement off to one side of the shade is not required whenever another circuit is connected to the fixture. When an appliance circuit is connected the conductors thereof lead off wholly without the shade of the fixture. They do not extend up into the shade where connection and disconnection is difficult.

While in the particular fixture which I shall describe in connection with the accompanying drawings the socket which mounts the lamp, supports the shade and provides the additional take-off connection, is supported in upright position above the mounting bracket, it is to be understood that the invention is not limited to the particular arrangement shown. The socket may be supported below the mounting bracket to give a drop instead of upright effect and the shade may be supported either in upright position as shown or in inverted position above or below the mounting bracket to give an indirect or semi-indirect effect.

In order to apprise those skilled in the art of the manner of constructing and using my invention I shall now describe an embodiment of the invention in connection with the accompanying drawings in which:

Figure 1 is a front elevational view of a fixture embodying the invention.

Figure 2 is a side elevation of the same partially in vertical section.

Figure 3 is a fragmentary elevational view showing the mounting of the shade upon the double socket supported at the upper end of the hollow stem carried by the mounting bracket; and

Figure 4 is an enlarged vertical axial section through the double socket.

In the embodiment of the invention selected for illustration, 5 designates the

mounting bracket. This bracket comprises a mounting base 6 having an outstanding hollow supporting arm 7.

Base 6 which is preferably made of sheet metal drawn or pressed into the desired configuration, although it may be made solid or otherwise formed, is attached to the wall 8 or other vertical support as by means of screws 9 and masks the outlet through which conductors 14 extend from the wall. Arm 7 is secured to base 6 by a machine screw 10 having threaded engagement with a lug 12 projecting obliquely from the inside of said arm 7 into engagement with base 6. Base 6 and arm 7 may be of any desired configuration and ornamented or trimmed as desired. The hollow arm 7, which is preferably cast, receives and masks conductors 14 which enter base 6 from wall 8 and extend up through hollow arm 7 as shown in dotted lines.

A hollow tubular stem 16 is secured to or terminates at its lower end in a head 17 having an opening 18 diametrically therethrough to permit leading conductors 14 into said head 17 and up through stem 16. Head 17 has a downwardly extending stud 19 which stud projects through and is soldered or otherwise secured in an opening in the outer end of arm 7. Stem 16 is bowed out around lamp or light 20 to permit vertical disposition of lamp 20 in the center of shade 25 as shown and extends up to and is mechanically attached as by soldering at 21 to the outer shell 22 of a fitting having aligned sockets 23 and 24 at its opposite ends.

Shade 25 is mounted in a cap or mounting bell 26 by means of thumb screws 27. The upper end of cap or bell 26 is reduced to snugly embrace shell 22 and said upper reduced end is provided with a bayonet slot 28. A pin 30 projecting from shell 22 is adapted to engage in slot 28 upon arrangement of cap 26 down over the upper end of shell 22 to secure the cap and shade 25 carried thereby in place.

Lower socket 24 opens downwardly to receive and support lamp 20 in vertical position there beneath and upper socket 23 which opens upwardly is employed for the attachment of an appliance circuit 35 as by means of a two part plug 31-32, part 32 having threaded engagement with socket 23 and part 31 having prong and socket engagement with part 32. An ornamental cap 36 is provided for attachment to plug portion 32 when appliance circuit 35 is disconnected. Cap 36 carries a tassel 38 for giving an ornamental appearance and improving the esthetic effect of the fixture when the appliance circuit is disconnected. This cap also seems to give a better finger hold for operating the plug 32 as a switch to turn the lamp 20 off or on at the lamp, when the appliance circuit is not connected. In Figures 1 and 2 cap 36 is shown in place with con-

necting plug 31 of appliance circuit 35 disconnected. In Figure 3 the appliance circuit is shown connected.

The double socket contained in shell 22 has a common central contact 40 (Figure 4). Contact 40 is mounted in an axial opening in a transverse partition of insulation 41. The upper projecting end of contact 40 is headed at 42 and a coiled spring 43 is interposed between head 42 and a metallic ring 44 on the upper surface of partition 41 around the axial opening therethrough. The lower end of contact stud 40 is headed at 45. Head 45 cooperates with a shoulder 46 in the opening through partition 41 to limit the upward movement of stud 40 under the action of spring 43. Shell 22 is lined with a layer of insulation 48 and aligned sockets 23 and 24 at the opposite ends of shell 22 comprise threaded conducting shells mounted within the sleeve or layer of insulation 48 at the opposite ends thereof.

Shell 22 is provided with an opening 50 at the upper end of stem 16 and conductors 14-14 are led into the double socket member through said opening. One conductor 14 is electrically connected with central contact 40 as by soldering it to ring 44 between which and head 42 spring 43 is interposed. The other conductor 14 is electrically connected to the threaded shells 23 and 24, as by leading it in and soldering it to one of said shells 23-24 and extending said conductor through partition 41 and connecting it to the other shell, as by soldering. It will be noted that central contact 40 is mounted to have engagement with the central contact of a plug inserted in upper circuit member 23 and is normally held in such position by spring 43 so that the central contact of a lamp or plug inserted in lower socket 24 cannot make contact with said common central contact 40 until the latter is pushed downwardly by the plug inserted in upper socket 23. When the plug is inserted in upper socket 23 it moves the common central contact 40 downwardly to bring lamp 20 into circuit. Consequently, the plug 32 in the upper socket 23 may serve as a switch for switching lamp 20 into and out of circuit.

From the foregoing it will now be apparent that I have provided a simple inexpensive wall fixture having an additional built-in outlet or take-off connection for an appliance or other electrical circuit. The connection of the appliance circuit is with a minimum of difficulty and without impairing the artistic effect of the fixture. The mounting of stem 16 and its extension around lamp 20 and up through shade 25 to the top thereof where it supports the double socket member gives the fixture the effect of a fixture of the upright type and at the same time lamp 20 is supported as in

a drop fixture with the advantageous lighting effect accompanying the same. The bayonet slot and pin connection between bell 26 and shell 22 provides a highly advantageous mounting for shade 25.

As already pointed out it is to be understood that the double socket may be suspended below mounting bracket 5 instead of supporting in upright position above said bracket as by extending supporting stem 16 downwardly instead of upwardly from arm 7 to give a drop instead of upright effect. The terms "up" and "down" are used herein not in a limiting but in an explanatory sense. Shade 25 may be supported either in upright position as shown or in inverted position above or below the mounting bracket.

I wish to call attention to the novel function of the plug 32 in this connection. It is obvious that instead of having an Edison socket in the shell 22 and then inserting a separable plug having push or prong contacts, the push or prong contacts might be directly mounted in the upper end of the shell. However, there is an advantage in the present construction, first, in that standard parts are used, and second, the use of the plug 32 in conjunction with the movable axial contact 40 permits the lamp 20 to be

switched off or on at the lamp, whether the implement circuit 35 is connected or not. The plug 32 in connection with contact 40 becomes a switch with an axially extending rotary handle or finger piece lying above 35 the upper end of sleeve 22 and at all times accessible for switching the lamp 20.

I do not intend to limit the invention to the precise details shown and described.

I claim:—

A double socket comprising a supporting member having an insulating partition therein, shell contacts at opposite ends of said supporting member and a shiftable contact controlled by the position of a plug member in one of said sockets, said shiftable contact comprising a contact stud mounted in the insulating partition, said stud having a head at one end cooperable with the partition to limit the movement of the stud therethrough, a head at the opposite end of said stud, and a coiled spring interposed between said head and a metallic ring mounted on the adjacent surface of the partition, electrical connection to the contact being had through said ring.

In witness whereof, I hereunto subscribe my name this 31 day of March, 1923.

EDMUND O. SCHWEITZER.
